UNITED STATES PATENT OFFICE.

FREDERICK R. BURCH, OF SEATTLE, WASHINGTON.

WIND MOTOR.

Application filed March 22, 1926. Serial No. 96,451.

This invention relates to wind-propelled motors or windmills.

The primary object of the present invention is to provide a motor of this character which will utilize the power of the wind to a greater extent than hitherto. Another object is to provide a motor construction wherein the windsails are arranged to revolve about a vertical axis and are interconnected with each other in a manner to cause all of them to operate simultaneously in the propulsion of the motor. Another object is to provide a wind motor which will be of durable construction and one which is peculiarly adapted for operating pumps for irrigation and other purposes requiring relatively large amounts of power.

More specific objects will appear in the following description.

20 The invention consists in the novel construction, adaptation and combination of parts hereinafter described and claimed.

In the accompanying drawings,—

Figure 1 is a view in vertical section of 25 a portion of a wind-motor illustrating an embodiment of the present invention. Fig. 2 is a plan view, somewhat diagrammatic, of the motor illustrating the arrangement of the sails and the controlling connections 30 therefor. Fig. 3 is a perspective view illustrating the preferred manner of securing the mast arms rigidly to the mast. Fig. 4 is a perspective view of a portion of the 35 mast and devices associated with the sail-controlling appliances. Fig. 5 is a fragmentary perspective view of one of the sail members.

In said drawing, the reference numeral 10 represents a rotary vertical shaft or mast 40 whose lower end is journaled in a foot bearing provided within a casing 11 which is desirably supported by means of gimbal devices 12, or an equivalent, above a foundation 13.

45 The upper end of the mast is journaled in a ring 14 which, in the illustrated embodiment, is connected as by means of guys 15 with suitable anchor posts or an equivalent, not shown, to maintain the mast substantially vertical.

Rigidly secured to the mast, as by means of cheek block 16 (Fig. 3) are pairs of radiating arms 17 and 18, four pairs being shown. The complementary arms 17 and 50 18 of each pair thereof are arranged par-

allel, or nearly so, with each other and in the same vertical plane.

Stay members 19 and 20 extend from the mast above and below each pair of arms to the outer ends of the latter, such ends also being connected with each other by a stay 60 comprising a central vertical member 21 having its ends connected to the ends of the adjacent mast-arms through the medium of swivel devices which are indicated by 22 65 in Fig. 1.

The association, above described, of the stays, and the mast-arms constitute a truss with respect to the mast and also serve to retain the ends of complementary arms 17, 70 18 in vertically spaced apart relations. The ends of the upper and lower tiers of arms 17 and 18, respectively, are connected with each other circumferentially of the motor by braces 23 as shown with respect to the upper 75 arms 17 in Fig. 2.

Secured intermediate their lengths to each of the stay members 21 are vertically spaced apart booms having arms 24¹ and 25¹ at one side of the respective stay member 21 and 80 arms 24² and 25² at the opposite side thereof.

The boom-arms 24² and 25² are connected with each other by crossed stays 26, each formed of complementary members which are adjustably coupled as by means of a 85 turn-buckle 27.

The purpose of the stays 26 is to maintain the companion booms substantially horizontal and in parallelism with each other.

The arms 24¹ and 25¹ of each pair of companion booms are, in proximity of their free ends, connected by a stay, such as indicated by 28 in Fig. 1, which is parallel with the stay member 21 to which the respective booms are secured.

95 Located between the arms 24¹ and 25¹ is a sail 29, preferably of canvas or other suitable flexible material; the lower edge of a sail being secured, as by lacings 30, to the boom arm 25¹; the upper edge of the sail 100 being secured, as by lacings 31, to a horizontally disposed pole member 32.

Between this member and the lower edge of the sail the latter is connected to one or more intermediate members, or cleats 33 two 105 being shown in Fig. 1. Said cleats are connected in horizontal positions to the sail as by lacings or, preferably, by means of strips 34 of flexible material which are sewed to the sail.

The ends of the pole member 32 and the cleats 33 are provided with apertures through which the stays 21 and 28 pass at opposite sides of the sail. As shown in

5 Fig. 5, a stay receiving aperture 35 is afforded by means of a metal strap element 36 secured to the extremity of a pole member 32, or cleat 33, and constitutes a part thereof.

10 The sails, guided by the stays 21 and 28, are individually hoisted by means of winches 38 secured to the mast and operating through the medium of halyards 37 passing about suitably arranged guide pulleys 39 and 39' and connected by the halyard end 37' to 15 the member 32 of the respective sail.

The sails may be lowered by gravitation when the halyards are permitted to unwind from the respective winches.

20 In furling and hoisting a sail the cleats 33 prevent excessive bagging of the same and also tend to maintain the sail in a plane when hoisted.

25 The booms 24¹—24² and 25¹—25², it is to be understood, are turnable about the axes of the respective stays 21 subject, however, to the regulation of the controlling means to be presently explained. The boom-arms 24¹ and 25¹ carry the sails therebetween; the complementary arms 24² and 25² act in conjunction with the braces 26 (Fig. 1) to maintain the booms in substantially horizontal planes. The boom arms 24² and 25² also serve as tiller elements with respect to the sails, each of such arms being connected by 30 a cable 40 (Fig. 2) with the sail carrying arm 24¹ and 25¹ of the sail next ahead in the direction of the orbital travel of the sails. The outer ends of boom arms 24¹—25¹ of the respective sails are coupled by means 35 of flexible connections (indicated generally by C and D in Fig. 2) with the outer ends of the corresponding boom arms of the respective sails at the diametrically opposite sides of the motor.

40 To this end, I provide for each pair of coupled boom-arms 24¹, or 25¹, a rod 41 extending through a tubular guide-way 42 (Figs. 1 and 4) extending, preferably, diametrically through the mast in substantially 45 the same horizontal plane in which the respective sail booms are located. The ends of each rod 41 are each connected with a cable extension 43 which is connected to the respective boom arms 24¹ and 25¹.

50 In the following description of operation with reference to Fig. 2, the boom arms 24¹ which carry the sails will, for clearness of explanation, be considered as the sails to which they respectively pertain, and are designated in successive full line positions which they occupy in their revolutions about the axis of the mast by A¹, A², A³ and A⁴; and in successive dotted line positions by 55 B¹, B², B³ and B⁴.

60 65 Assuming the wind is blowing in the di-

rection indicated by arrows W in Fig. 2, the motor will rotate to cause the sails to revolve in the direction indicated by the arrow R.

With the wind thus blowing, the sails 70 when rotated into their relative dotted line positions B¹, B², B³, B⁴, are also brought into their critical positions, so to speak, whereat they are influenced by the force of the wind to simultaneously swing them from 75 such critical (dotted-line) positions into their full line positions A¹, A², A³, and A⁴. All of the sails remain in the last referred to relative angular positions with respect to each other during the following one- 80 fourth of a revolution or into the critical positions in which they are represented in Fig. 2 by dotted lines B², B³, B⁴, and B¹, respectively.

85 The angularity of the sails with respect to each other does not change until they reach their critical positions, as shown by dotted lines; but at such critical positions, the sails are simultaneously swung into positions corresponding to the full lines, and 90 so on, the sails changing their angular relations with each other at the successive one-fourth revolutions. The regulation of the sails to meet the above explained periodic changing of their angular relations is ac- 95 complished by the effective force of the wind acting against all of the sails, subject to the conjoint action of the flexible connections 40 and C—D.

100 The mutual actions of said flexible connections will be understood by an inspection of Fig. 2 and may be explained as follows: Assuming the sails are in their critical po- 105 sitions—B¹, B², B³, and B⁴; the sails B² and B⁴ are most powerfully affected by the wind, which acting upon the same, cause them to 110 be swung into their A² and A⁴ positions, re- spectively.

115 In being thus influenced, the referred to sails act through the medium of the cables 110 40 (subject to the constrained action of the cross connection C) will cause the other two sails to be swung from their B¹ and B³ positions into their A¹ and A³ positions.

120 During such changing positions of the sails, all of the cables 40 remain taut excepting those indicated by 40^a becoming slack and those indicated by 40^b bearing taut. It is thus seen that the cables 40 cooperate with the flexible cross connections C and D to 125 regulate the angular relations of the sails at all times.

130 The construction of the invention, as now preferred by me, and its operation will, it is believed, be understood from the foregoing 125 description.

What I claim is,—

1. In a wind motor, the combination with a rotatable mast having pairs of arms radiating therefrom, the arms of each pair 130

- thereof being located one above the other, of sails positioned between each pair of arms for rotary movements about individual axes extending vertically through the respective 5 arms, sail-supporting means permitting the spreading and furling of said sails, and flexible means extending between and having their ends connected to the adjacent sails circumferentially of the motor for mutually 10 influencing the sails in the rotative actions thereof about their respective axes in each cycle of revolution of the sails about the mast axis.
2. In a wind motor, the combination with 15 a rotatable mast and mast arms radiating therefrom, sails pivotally associated with said arms for rotative movement about substantially vertical axes, cables connecting the successive sails with each other circumferentially of the motor, and means coupling the 20 sails at diametrically opposite sides of the mast for controlling the action of the respective cables.
3. In a wind motor, the combination with 25 a rotatable mast provided with arms radiating therefrom, sails pivotally associated with said arms for rotative movement about substantially vertical axes, cables connecting the successive sails with each other circumferentially of the motor, and means coupling the 30 sails at diametrically opposite sides of the motor and cooperating with cables for controlling the angular relation of the sails with respect to each other.
- 35 4. In a wind motor, a mast, arms extending therefrom sails carried by said arms in pivotal relation therewith, sail direction regulating means connecting the sails with each other successively circumferentially of the 40 motor, and other sail direction regulating means connecting the alternate sails diametrically of the mast and cooperating with the first named means whereby the power of the wind acting through the medium of the 45 sails serve to regulate the angular relation of the latter with respect to each other.
5. In a wind motor, a series of sails rotatable about individual vertical axes and arranged for revoluble travel about a vertical axis, and means connecting the sails with each other and adapted to cooperate with the power of the wind acting through the medium of the sails for periodically and simultaneously changing the angular relations of the sails with respect to each other 50 at substantially each one-fourth of a cycle of revolution of the sails, said means also serving to retain the sails in substantially unchanging angular relations with respect to each other at other positions of their travel.
6. In a wind motor, a mast having two sets of radiating arms disposed at different elevations, stays connecting the complementary arms of each set thereof, sails connected 55 to the respective stays, a head boom and a foot boom for each sail, means for raising and lowering the respective sails, regulating means connecting the booms of the respective sails with each other, and means extending through apertures provided in the 60 mast to cooperate with said regulating means to effect rotary movements to all of the sails upon the respective stays in each cycle of revolution of the sails.
7. In a wind motor, a mast having two sets of radiating arms disposed at different elevations, stays connecting the complementary arms of each set thereof, sails connected to the respective stays, a head boom and a foot boom for each sail, braces maintaining the 65 booms of each sail parallel with each other, means for raising and lowering the respective sails, regulating cables connecting the booms of the adjacent sails with each other, and flexible means coupling the 70 booms of each pair of sails cooperating with said cables serving to impart relative rotary movement simultaneously to all of the sails and at predetermined intervals in each revolution of the sails about the axis of the 75 mast.
8. In a wind motor, a mast having two sets of radiating arms disposed at different elevations, stays connecting the complementary arms of each set thereof, sails positioned 80 between the respective complementary arms, a head boom and a foot boom for each sail, said booms being pivotally connected to the respectively stays, other stays connecting the 85 booms of each sail and disposed in parallel relation with the respective arm-connecting stays, means for raising and lowering the respective sails, regulating means connecting the booms of the sails with each other circumferentially of the motor, and means connected to the booms of the sails at diametrically 90 opposite sides of the motor to cooperate with said regulating means to control the individual rotary movements of all of the sails responsive to the power of the wind.
9. In a wind motor, a rotary mast, two sets of arms radiating therefrom in vertically spaced-apart relation, stays connecting the outer ends of complementary arms of both sets thereof, a pair of booms one above 95 the other pivotally connected intermediate their lengths to each of said stays to provide boom arms at opposite sides of the same, a second stay connecting the corresponding arms of each pair of booms, a pole 100 member between each pair of booms, said pole members being slidably connected for vertical movement to the respective stays, sails connected at their upper and lower 105 ends to the poles and lower boom arms, respectively, sail hoisting means, and flexible means connecting both arms of each of the booms with the arms of the other booms for regulating the angularity of the sails with 110 respect to one another.

10. In a wind motor, a rotary mast, two sets of arms radiating therefrom in vertically spaced-apart relation, stays connecting the outer ends of complementary arms of 5 both sets thereof, stays extending from said arm ends to the mast, a pair of booms pivotally connected intermediate their lengths to each of the first named stays to provide boom arms at opposite sides of the same, a 10 sail between each pair of booms, the foot thereof being connected to an arm of a lower boom, means connected to the sail for raising and lowering the sail, and sail regulating means connecting the sail carrying arms of 15 each boom with the other arms of an adjacent pair of booms.

11. In a wind motor having sails revolvable about an axis common to all of the sails and rotatable about individual axes for the 20 respective sails, of direction regulating means for said sails comprising flexible devices connecting the sails one with another in series circumferentially of the motor, and sail governing means connecting the booms 25 in pairs diametrically of the motor.

12. In a wind motor, two booms disposed at different elevations, two vertical stays disposed in horizontally spaced apart rela-

tion, the ends of said stays being connected to the respective booms, a horizontal pole 30 member and a horizontal cleat member connected at its ends to said stays for vertical movement, a sail, said sail being connected at its upper and lower ends to the pole and the lower boom, respectively, and intermediate 35 its height to the cleat member, and means connected to the pole for raising and lowering the sail from and to said lower boom.

13. In a wind motor, two booms disposed at different elevations, a vertical stay connecting said booms to provide the latter with sail carrying arms at one side of the stay and tiller arms at the opposite side, braces connecting said tiller arms for retaining the booms parallel with each other, a vertical 40 stay connecting the outer ends of sail carrying arms, a pole member connected for vertical movement to said stays, a sail having its upper and lower ends respectively connected to the pole and the sail carrying arm of the 45 lower boom, and means connected to said pole for regulating the same to raise and lower the sail.

Signed at Seattle, Washington, this 18th day of February, 1926.

FREDERICK R. BURCH.
